UNITED STATES PATENT OFFICE.

MARGARET TINGLE, OF CLEVELAND, OHIO.

ADJUSTABLE CUFF.

Application filed March 24, 1924. Serial No. 701,378.

To all whom it may concern:

Be it known that I, MARGARET TINGLE, a citizen of the United States, and a resident of Cleveland, county of Cuyahoga, and State of Ohio, have invented a new and useful Improvement in Adjustable Cuffs, of which the following is a specification, the principle of the invention being herein explained and the best mode in which I have contemplated applying that principle, so as to distinguish it from other inventions.

This invention relates to an adjustable cuff for men's shirts. More particularly the invention comprises the supplying of a plurality of button-holes and eyelets in the upper portion of the cuff-band of the usual fold back cuff of the type used on men's shirts and the like, in order that a plurality of links or other fastening elements may be placed therethrough so as to provide two fastening elements in the cuff itself in place of the single pair of links usually employed. The button-holes and eyelets are so placed that when the cuff is folded in the usual manner but a single button-hole adjacent each end will be shown, the inner fastening link or snap button passing through the inner sections of the cuff only and being concealed beneath the turned back portion. The provision of a plurality of button-holes and eyelets permits the use of a plurality of lines upon which the cuff may be folded so that the life of the garment will be prolonged through the distribution of the wear at the edge over several folding lines and at the same time prevents a cuff having such plurality of button-holes showing a tendency to spread adjacent the point at which the link is placed so as to be unsightly and uncomfortable for the wearer.

Cuffs of the fold back type provided with a plurality of button holes so that the same could be folded across two transverse lines are old in the art, but, as has already been indicated, such cuffs have the disadvantage of shifting the position of the link away from or toward the edge of the cuff to such a degree that the cuff no longer hangs true. The principal object of the invention is to provide an improved adjustable cuff adapted to be folded upon a plurality of lines. A further object of the invention is to provide a plurality of positive securing elements passing through the several sections of the cuff itself, which will serve to hold the same in perfect fitting adjustment about the wrist

of the wearer and in so firm a manner that such adjustment will not be disturbed under any conditions of use. Other objects of the invention will appear in the course of the following description. To the accomplishment of the foregoing and related ends, said invention, then, consists of the means hereinafter fully described and particularly pointed out in the claims.

The annexed drawing and the following description set forth in detail certain structure embodying the invention, such disclosed means constituting, however, but one of various structural forms in which the principle of the invention may be used.

In said annexed drawing:—

Fig. 1 is a plan view of a cuff provided with button-holes and eyelets forming the subject-matter of this invention; Fig. 2 is a perspective view of a cuff provided with button-holes and eyelets with such cuff adjusted for use upon the upper line of folding; Fig. 3 is a perspective view partially in section, taken along the line 3—3 shown in Fig. 2, looking in the direction of the arrows; Fig. 4 is a perspective view of a cuff provided with button-holes and eyelets and with such cuff adjusted for use upon the lower line of the folding; and Fig. 5 is a perspective view partially in section, taken along the line 4—4 shown in Fig. 4.

As is clearly shown in Fig. 1, a cuff 1 of the usual type is attached to the lower end 2 of a shirt or other garment and is of suitable length to be folded back upon itself along an intermediate transverse line of folding. As is clearly indicated in said Fig. 1, two lines of folding are provided, the first line 3 being intended for use in the first instance, and the second line 4 being intended for use after the cuff has become soiled or worn along the line 3. In order to secure the cuff, when folded, upon the alternate lines of folding, the cuff is provided at each of its lateral edges with three button-holes and two eyelets. The button-holes 5, placed at an intermediate position in the lower section of the cuff, are designed to receive the links which are customarily used with folded back cuffs of this character. Said button-holes, when the cuff is folded upon the first line of folding, are adapted to register with button-holes 6—6 positioned slightly above a transverse central line through the upper section of the cuff. When the cuff is folded upon the lower line of folding, the button-holes

5—5 are adapted to be brought into register with the button-holes 7—7, positioned slightly below a transverse central line through the upper section of the cuff. Immediately 5 above each of the button-holes 6, an eyelet 8 is provided, and immediately beneath each of the button-holes 7, an eyelet 9 is provided. As is clearly shown in Fig. 3, when the 10 cuff is folded upon the upper line of folding and the button-holes 5, 6, are in registry, and the cuff link 11 placed through such button-holes, an auxiliary link or other fastening device, such as a separable snap fastener 12, is secured through the eyelets 9.

15 Thus, when secured as above described, the cuff will present the appearance shown in Fig. 2 and will be held securely against disarrangement or spreading by the double fastening. As is clearly shown in Fig. 2, 20 the only fastening element apparent to the observer is the usual cuff link 11 which passes through both the upper and lower folded portions or four folds of the cuff, but the auxiliary fastening element concealed within the fold of the cuff and passing 25 through only the folded upper section of the cuff is the means which co-acts with the other fastening element to hold the cuff in secure and permanent adjustment about the 30 wrist of the wearer.

When the cuff, as disclosed in Figs. 2 and 3, shows signs of wear along the upper line of folding or when said cuff becomes soiled and a temporary unsmeared edge is found desirable by the wearer, the cuff is folded along the lower line of folding, as is shown 35 in Fig. 4. When so folded the button-holes 5 are brought into register with the button-holes 7 and the link 11 is placed there- 40 through. The eyelets 8, adjacent the upper portion of the cuff, are used to receive the auxiliary link or fastening element 12. In this position of adjustment the auxiliary link will also be concealed from view and 45 the spreading or flaring of the cuff adjacent its point of attachment to the band will be effectively prevented.

It is obvious that the proportions of the cuff will be varied with the size of the shirt to which it is attached and the positioning of the button-holes and eyelets will be varied in accordance with the depth of the cuff, the character of the material, and the degree of spacing desired between the several lines of folding. The cuff may be so constructed as to have its upper edge overlap the point of attachment of the cuff to the lower edge of the sleeve under either position of adjustment or may be so constructed that it will not overlap the point of connection with the sleeve in either position of adjustment. The cuff may also be so arranged that its upper edge will overlap the point of attachment to the lower edge of the sleeve when the cuff is in its upper position of adjustment and

have its upper edge come slightly below said line of attachment when the cuff is in its lower position of adjustment.

By thus having each cuff held by two fastening devices, one the link usually employed, and the other a shorter fastening element concealed within the fold and connecting the inner portions of the cuff only, a perfect fitting cuff is provided for and one which will not spread on either its upper or lower side regardless of how much strain the cuff is subjected to. The button and button-hole frequently provided upon the fly of the sleeve portion of a man's shirt, just above the point of attachment of the cuff, is entirely unnecessary and the set and fit of the cuff with the double means of attachment herein provided for is superior to any fit which can be obtained through the use of such button and button-hole on the fly with the button-holes for the cuff in the usual position.

The cuff is so firmly secured that it maintains its form perfectly, regardless of what activities are engaged in by the wearer.

A further advantage of the cuff is that it will enable a person wearing a certain length of sleeve to purchase a shirt having a sleeve size a trifle longer or shorter than the required size and use such shirt with the cuff links in the proper button-hole to bring the cuff in proper relation to the edge of the coat sleeve. For this and similar purposes it may be found desirable to provide more than two lines of folding across the cuff and in such event an additional pair of button-holes will have to be provided in the upper section of the cuff.

Other modes of applying the principle of my invention may be employed instead of the one explained, change being made as regards the structure herein disclosed, provided the means stated by any of the following claims or the equivalent of such stated means be employed.

I therefore particularly point out and distinctly claim as my invention:—

1. A foldable cuff attached at its upper edge to a sleeve, a pair of button-holes positioned adjacent each side edge of said cuff, a pair of eyelets provided adjacent the upper button-holes and in spaced relation thereto, said button-holes and eyelets, respectively, being adapted to be placed in registry when said cuff is folded into position for wear.

2. A foldable cuff provided with a plurality of button-holes and eyelets, one pair of said button-holes being adapted to register selectively with either of two other pairs of button-holes to receive a fastening member, thereby providing an alternative line of folding for said cuff, and said eyelets providing means to receive a fastening element for holding said cuff at a point spaced from said registering button-holes.

3. A foldable cuff provided with three button-holes adjacent each of said outer edges, the lowermost of said button-holes being adapted to be folded into registry with either of the button-holes positioned above the same, a pair of eyelets positioned above and below the two upper button-holes at each side of said cuffs, said eyelets providing means for receiving a fastening element at a point spaced from the fastening element inserted through said registering button-holes.
4. A cuff foldable upon itself at an intermediate transverse line, a series of button-holes adapted to be placed in registry to receive a fastening member, and a pair of eyelets formed in the inner portions of said folded cuff and adapted to be positioned in registry when said button-holes are in registry with each other to receive an auxiliary fastening member.
5. A cuff foldable upon itself at an intermediate transverse line, a pair of button-holes positioned adjacent the outer edges of said cuff at an intermediate position below said transverse line of folding, a pair of button-holes positioned adjacent each side of the outer edge of said cuff above said intermediate transverse line of folding, a pair of eyelets positioned above and below each of said pairs of button-holes in the upper section of said cuffs, said eyelets being in continuous registry in pairs with each other, and said button-holes beneath said intermediate transverse line of folding being adapted to be brought selectively into registry with either of the button-holes in the other portion of said cuff.

Signed by me, this 15th day of March, 1924.

(MRS.) MARGARET TINGLE.
